UNITED STATES PATENT OFFICE.

ROBERT HABERTHÜR AND RUDOLPH BRENNER, OF NEW YORK, N. Y.

RETORT-DOOR.

SPECIFICATION forming part of Letters Patent No. 392,202, dated November 6, 1888.

Application filed October 7, 1887. Serial No. 251,730. (No model.)

To all whom it may concern:

Be it known that we, ROBERT HABERTHÜR and RUDOLPH BRENNER, both of New York, county and State of New York, have invented 5 a new and Improved Door for Retorts, of which the following is a specification.

This invention relates to a door for gas-retorts, so constructed that it may be adjusted to make tight joints with the door-frame.

10 The invention consists in the various features of improvement, more fully pointed out in the claims.

In the accompanying drawings, Figure 1 is a face view of our improved door for gas-retorts; Fig. 2, a sectional top view thereof; and Fig. 3, a vertical central section on the line *x*-*x*, Fig. 1.

15 The letter *a* represents the door-frame, made of **D** form and adapted to be secured to the mouth of a retort.

20 *b* is the door, hinged upon a pintle, *c*, the ends of which are secured to lugs *d*, projecting rearwardly from frame *a*. The door is hung upon the pintle by means of an arm or 25 block, *f*, having the two cylindrical sleeves *f'* *f''*, that embrace pintle *c*. The bore of each sleeve is somewhat larger in diameter than the diameter of the pintle, Fig. 2, so that the door has a play upon its pivot.

30 *g*, *g'* and *h*, *h'* are screws passing through each of the sleeves *f'* and abutting against pintle *c*, the screws *g*, *g'* being placed opposite one another and the screws *h*, *h'* being also placed opposite one another. By loosening the screws 35 *g* and tightening up the screws *g'*, or vice versa, the door may be shifted laterally, and by operating the screws *h*, *h'* in similar manner the door may be thrown farther inward or outward. Thus the door may be adjusted in four 40 different directions.

The inner edge of the frame *a* should be beveled, Fig. 3, and the door should be correspondingly beveled to make a good joint. The lowermost bar, *a'*, of the frame *a* is cut away 45 at the front to accommodate a slide, *i*, bearing against the lowermost edge of door *b*. This

slide has also a beveled top edge, and it is held to the bar *a'* by means of a pair of screws, *j*, passing through elongated upright slots in slide *i*. By first loosening these screws the slide may 50 be moved upward toward the door, when the joint is to be tightened up, after which the slide may be locked in place by the screws.

k is a locking-bar pivoted to door *b* by pivot *k'* and free to be oscillated between stops *k''*. 55 The free end of the bar *k* may be engaged and pressed against the frame *a* by means of a cam-lever, *l*, pivoted to a lug, *m*, on such frame. The cam-lever *l* is provided with socket or sleeve *l'* for the introduction of a hand-lever. The door is unlocked by swinging the cam-lever aside, and then swinging the locking-bar upward to clear such lever, after which the door 60 may be opened.

What we claim is—

1. The combination of door-frame *a*, having lugs *d*, with pintle *c*, secured to such lugs, and 70 with door *b*, having sleeves *f'*, that embrace the pintle between lugs *d*, and which have a bore greater than the diameter of the pintle, and with the screws *g*, *g'*, *h*, *h'*, passing through sleeves *f'* and abutting against pintle *c*, substantially as specified.

2. The combination of **D**-shaped frame *a*, beveled at its inner edge, with a hinged beveled door, *b*, and with a slide, *i*, secured to the bar *a'* of frame *a* and bearing against the edge 80 of door *b*, substantially as specified.

3. The combination of door *b*, having pivoted locking-bar *k*, with door-frame *a*, having lug *m*, and cam-lever *l*, pivoted to lug *m*, and provided with socket *l'*, the locking-bar *k* being placed between the door and the cam-lever, substantially as specified.

ROBERT HABERTHÜR,
RUDOLPH BRENNER.
